UNITED STATES PATENT OFFICE.

CLIFTON H. BEACH, OF PITTSBURG, PENNSYLVANIA, ASSIGNOR TO THE
SALTSBURG BOTTLE WORKS COMPANY, LIMITED, OF SAME PLACE.

DESIGN FOR A BOTTLE.

SPECIFICATION forming part of Design No. 22,167, dated January 31, 1893.

Application filed December 12, 1892. Serial No. 454,975. Term of patent 7 years.

To all whom it may concern:

Be it known that I, CLIFTON H. BEACH, a citizen of the United States, and a resident of Pittsburgh, in the county of Allegheny and State of Pennsylvania, have invented and produced a new and original Design for Bottles; and I do hereby declare that the following is a full, clear, and exact description thereof, which will enable others skilled in the art to 10 which it appertains to make and use the same.

In the accompanying drawings, Figure 1 is an elevation of a bottle, showing my design, and Fig. 2 is a longitudinal section of the same; these two views being deemed necessary to fully illustrate my design.

The design consists in a bottle comprising a cylindrical body, a rounded lower portion, a bottom of less diameter than the body, a neck, a sloping upper portion intermediate the neck and the body, an annular shoulder at the junction of the neck and upper portion, an annular bead formed with a double bevel at the end of the neck, and a bead of smaller diameter just below said first-mentioned bead.

Referring by letter to the said drawings, A designates the cylindrical body portion, B the

bottom of less diameter than the said body, C the rounded lower portion connecting the bottom with the body, D the neck, E the sloping upper portion intermediate the neck and cylindrical body, F the annular shoulder at the junction of the said sloping portion and the neck, H the double beveled annular bead at the upper end of the bottle, and G the beveled bead located just below bead H.

What I claim is:

The herein-described design for bottles, comprising the cylindrical body rounded at its lower end, the sloping upper part between 40 said cylindrical body and the neck, and the neck having at its lower end an annular bead or shoulder separating it from the sloping upper part of the bottle, and at its upper end or top two beveled beads contiguous to each 45 other, but the upper bead overlapping the lower, as shown and specified.

In testimony that I claim the foregoing as my own I have hereunto affixed my signature in presence of two witnesses.

CLIFTON H. BEACH.
